TYPOGRAPHICAL COMPOSING MACHINE

Paul Hilpman, Garden City, and William J. Bahm,
Brooklyn, N. Y., assignors to Mergenthaler
Linotype Company, a corporation of New York

Application March 9, 1951, Serial No. 214,804

10 Claims. (Cl. 199—18)

2

This invention relates to typographical composing machines, such as Linotype machines of the general organization represented in U. S. Letters Patent to O. Mergenthaler, No. 436,532, wherein circulating matrices are released from a magazine in the order in which they are to appear in print and then assembled in line, the composed line delivered to the face of a mold, the mold filled with molten metal to form a type bar or slug against the matrices, and the matrices thereafter returned through a distributing mechanism to the magazine from which they started.

More particularly, the invention is applicable to machines which are equipped with hinged assembly mechanisms of the type shown and described in the pending application of L. Rossetto et al., Serial No. 184,072, filed September 9, 1950, where practically the entire matrix assembling mechanism is mounted in a hinged supporting frame which may be swung from and to its operative position at will, not only to give access to the interior parts of the mechanism, but also to give complete access to an auxiliary reed supporting frame which, as disclosed in said application, is detachably connected to the fixed machine frame so that the entire bank of reeds may be removed as a unit.

Since the line resistant finger against which the matrices are composed in the assembler elevator is slidably mounted in the hinged supporting frame for the swinging assembling mechanism, the assembler elevator must first be raised to remove it from the path of travel of the line resistant finger before the frame is swung to inoperative position. Toward this end, means are provided to prevent the unlocking of the hinged supporting frame when the assembler elevator is in the composing position and, in addition, to support the assembler elevator in its raised position after the frame has been unlocked and swung from its operative position.

If at the time the hinged supporting frame is swung from its operative position any matrices should be lodged between the discharge end of the magazine and the top of the frame, damage to the matrices or to the machine parts would be apt to occur. Hence, further means are provided to prevent the unlocking of the supporting frame until the usual matrix feeler member (described in the aforesaid application) is first operated. Likewise, to prevent any matrices from being accidentally released from the magazine while the swinging frame is open, the matrix feeler is maintained in its blocking position across the discharge end of the magazine.

These and other improvements will be brought out in the drawings and in the description following; and for a complete understanding of the machine to which the present improvements are particularly applicable, reference may be had to the above cited application.

Referring to the drawings:

Fig. 1 is a front elevation of the hinged assembler frame as mounted in the machine;

Fig. 2 is a perspective view of the locking device for the hinged assembler frame and the safety mechanism associated therewith;

Fig. 3 is an edge view of the locking block attached to the hinged assembler frame;

Fig. 4 is a top plan view showing the manner in which the hinged frame is locked in operative position;

Fig. 5 is a fragmentary front view, partly in cross section, to illustrate the operation of one of the safety devices;

Fig. 6 is a right side elevation of the parts shown in Fig. 2;

Fig. 7 is a front elevational section taken along the line 7—7 of Fig. 6;

Fig. 8 is a left side view of parts shown in Fig. 7; and

Fig. 9 is a right side elevation of a portion of the machine to which the present invention is applicable, showing the matrix feeler and its manner of operation.

The matrices are individually released from a magazine A and fall by gravity into the vertically disposed assembler entrance comprising, as usual, a back plate 1, a hinged front plate (not shown) and intermediate partition plates 2 providing vertical channels for guiding the matrices in their fall. As the matrices issue from the entrance channels, they pass onto the upper stretch of an inclined continuously moving belt 3, passing around a lower driving pulley 4 and an upper idler pulley 5, whereupon they pass through and are discharged by a guide chute 6 in front of a continuously rotating star wheel 7 which stacks them, one by one, in line in an assembler elevator B against a yielding line resistant finger 8. When the line of composed matrices has been completed, the assembler B is elevated and the composed line transferred to casting position.

The line resistant 8 is carried by a long slide 9 which is provided, as usual, with an adjustable stop 10 set to control the length of line to be composed; and a brake 11, cooperating with the slide 9, serves to prevent retrograde movement of the slide until the composition of the line is completed. A solenoid controlled brake release mechanism 12 is operated to compress the line and to

straighten up the matrices, particularly the last matrix, preparatory to the raising of the assembler elevator. When the assembler is raised and the brake 11 released, the line resistant is returned to rightward position in readiness for the composition of the next line as soon as the assembler is returned to line receiving position.

All of the assembling elements thus far described and denoted by reference numerals are mounted upon and carried by a supporting frame 13 which is hinged at the right to the fixed machine frame C, as at 14, for a forward and rearward swinging movement. By being so mounted in the frame 13, these and other elements of the assembling mechanism may be swung from and to operative position at will, not only to give access to the interior parts of such mechanism, but also to give complete access to a removable frame in which the escapement reeds are mounted as a bank. In this connection, it should be noted that the line resistant 8, which also is mounted on the swinging frame 13, is normally operative within the confines of the assembler B when the latter is in lowermost or line receiving position and, hence, the assembler should be raised high enough to clear the line resistant before the frame is swung open.

The swinging frame 13 is held in closed position by means of a rotary locking pawl 15 (see Fig. 4) radiating from a short fore-and-aft shaft 16 which is operable by a handle 17 conveniently located at the front of the machine. The shaft 16 is rotatably supported in the fixed face plate 18 of the machine frame and is given additional support by a downwardly depending arm 19 which is attached to the front of the face plate. Fore-and-aft play of the shaft is prevented by a pair of collars 20. As best shown in Figs. 3 and 4, when in locked position the pawl 15 is adapted to engage a slotted block 21 mounted on the rear of the frame 13. To relieve strain on the hinges 14, the arm 19 is provided with an outstanding ledge 19^a carrying an adjustable set screw 19^b which acts against the under surface 21^a of the slotted block 21 and thereby lends additional support to the swinging frame 13 in locked or operative position.

As mentioned above, the hinged frame 13 cannot be swung to open or inoperative position unless the assembler B is first elevated out of the path of the line resistant 8. As a safeguard against completely unlocking the swinging frame while the assembler is in line receiving position, there is provided a latch 22, centrally pivoted at 22^a to the member 19 and actuated from the handle 17 by an eccentric 23 (see Fig. 5) formed on the shaft 16 and passing through an elliptical hole 24 of the latch. If the assembler has not been raised, the lower portion of the latch will strike part of the assembler elevator and prevent the complete release of the pawl 15 from the slotted block 21 (see Fig. 1). If, on the other hand, the assembler has been sufficiently raised to stand clear of the line resistant finger 8, the safety latch 22 will be free to move, not only far enough to permit the swinging frame 13 to be unlocked, but also far enough to be placed in position underneath the assembler and to support it in its thus elevated position so that the frame 13 may be swung back into place at any time without repeating the elevator raising operation.

As an added safety feature of the present invention, the complete release of the locking pawl 15 from the block 21 is further prevented unless

the usual matrix feeler member 25 is first actuated. The matrix feeler operating mechanism is described in considerable detail in the aforementioned application, and consequently only as much of that mechanism as is absolutely necessary for a complete understanding of the present invention is shown in the drawings. As best shown in Fig. 8, the matrix feeler bar 25, which is arranged to be moved across the lower or discharge end of the active magazine A to detect the presence of matrices protruding therefrom, is operated from a hand lever 26 located at the front right hand side of the machine. The hand lever is fast to a rotatable horizontally disposed shaft 27 journaled in suitable bearings in the fixed machine frame and provided at its opposite ends with short crank arms 28. These crank arms 28 are connected by means of centrally pivoted levers 29 to operating slides 25^a, whereby the matrix feeler bar 25 is actuated when the hand lever 26 is depressed. The feeler bar 25, after actuation, is returned to normal inoperative position by a spring 29^b acting through a link 29^c pivotally connected to the upper end of one of the levers 29.

In order to insure the operation of the feeler bar 25 prior to the unlocking of the swinging frame 13, the hand shaft 16 is provided with a rearward extension 16^a having a locking disk 30. This disk 30 presents an arcuate portion 30^a bounded in part by a straight edge 30^b, which latter, as shown by dotted lines in Figs. 2 and 7, will normally contact the rightwardly disposed crank arm 28 below its axis of rotation and thereby prevent the pawl 15 from being turned to unlocking position. The said crank arm is, however, provided with a recess or cutaway portion 28^a so located that, when the crank arm is rotated by the depression of hand lever 26 to actuate the feeler bar 25, the locking edge 30^a will be free to enter the recess 28^a and permit the turning of the pawl 15 to unlocking position, provided, of course, that the assembler elevator B has been raised sufficiently to allow the latch 22 to pivot into elevator supporting position.

In being turned from locking to unlocking position, the pawl 15 rotates through an angle of approximately 90° and so does the locking disk. Hence, after actuation, the feeler bar 25 is retained in operative position across the discharge end of the active magazine A by the engagement of the arcuate portion 30^a of the disk 30 with the flat face of the cutaway portion 28^a of the crank arm 28, as shown by the solid lines in Figs. 2, 6, 7 and 8, it being observed that said arcuate portion 30^a, like the straight edge 30^b, is arranged to engage the crank arm below its axis of rotation. The dotted lines in Fig. 8 represent the normal position of the crank arm, i. e. before the hand lever 26 is depressed to actuate the feeler bar 25; whereas the solid lines in said figure represent the position of the crank arm after the depression of the hand lever and with its recess or cutaway portion 28^a in position to afford clearance for the locking disk 30.

Preferably the sequence of operations for unlocking the swinging frame 13 is as follows. The assembler elevator is first raised and the handle 17 rotated until the straight edge 30^b of the locking disk 30 contacts the crank arm 28. In this position of the parts, the latch 22 has been sufficiently pivoted to support the elevator in raised position. Thereupon, the hand lever 26 is depressed, moving the feeler bar 25 across the discharge end of the active magazine and at the

same time bringing clearance recess 28^a into position to receive the disk 30, so that the handle 17 can now be fully turned to completely disengage the pawl 15 from the slotted block 21. In this unlocked condition of the frame 13, the locking disk 30, by the engagement of its arcuate portion 30^a with the flat face of the recess 28^a in the crank arm 28, will prevent the return of the feeler bar 25 to its normal or matrix releasing position. In relocking the swinging frame 13, the operation of the parts is simply reversed, the latch 22, when the pawl 15 fully reenters the slotted block 21, being pivoted from its elevator supporting position and permitting the latter to fall by gravity to the line receiving position.

It should be understood that the present invention has been shown in only a single form and by way of example, but obviously, many variations and modifications may be made therein which will still be comprised within its spirit. It is to be understood, therefore, that the invention is not limited to any specific form or embodiment, except insofar as such limitations are specified in the appended claims.

What is claimed is:

1. In a typographical composing machine equipped with a matrix feeler movable across the discharge end of the magazine in the absence of protruding matrices, the combination of an assembling mechanism mounted on a hinged frame for movement from and to its operative position, a lock to hold the frame in its operative position, and a normally active safety device to prevent the release of said lock, said safety device being deactivated by the movement of the matrix feeler across the discharge end of the magazine.

2. A combination according to claim 1, wherein the safety device includes means to maintain the matrix feeler in its thus operated position until the lock is restored to locking position.

3. In a typographical composing machine equipped with a matrix feeler movable across the discharge end of the magazine in the absence of protruding matrices, the combination of hand operated means for actuating the matrix feeler, an assembling mechanism mounted on a hinged frame for movement from and to its operative position, a lock to hold the frame in its operative position, and a safety device to prevent the release of said lock and normally engaged with an element of the hand operated means for actuating the matrix feeler, said element being disengaged from the safety device to deactivate it when the matrix feeler has been moved across the discharge end of the magazine.

4. In a typographical composing machine equipped an assembler elevator in which matrices are composed in line and a matrix feeler movable across the discharge end of the magazine in the absence of protruding matrices, the combination of an assembling mechanism mounted on a hinged frame for movement from and to its operative position, a lock to hold the frame in its operative position, a normally active safety device to prevent the release of said lock, said safety device being deactivated by the raising of the assembler elevator from its line composing

position, and a second normally active safety device to prevent the release of said lock, said second safety device being deactivated by the movement of the matrix feeler across the discharge end of the magazine.

5. A combination according to claim 4, including common means for operating the lock and the two safety devices.

6. A combination according to claim 4, including a single rotary handle for operating the lock and the two safety devices in proper sequence.

7. In a typographical composing machine equipped with a matrix feeler movable across the discharge end of the magazine in the absence of protruding matrices, the combination of hand operated means for actuating the matrix feeler, an assembling mechanism mounted on a hinged frame for movement from and to its operative position, a lock to hold the frame in its operative position, means for normally obstructing the release of said lock, and means controlled by said hand operated means for removing the obstruction to the release of the lock when the matrix feeler is moved across the discharge end of the magazine.

8. In a typographical composing machine equipped with a matrix feeler movable across the discharge end of the magazine in the absence of protruding matrices, the combination of hand operated means for actuating the matrix feeler, an assembling mechanism mounted on a hinged frame for movement from and to its operative position, a lock to hold the frame in its operative position, means for normally obstructing the release of said lock, means controlled by said hand operated means for removing the obstruction to the release of the lock when the matrix feeler is moved across the discharge end of the magazine, and means for maintaining the matrix feeler in such actuated position across the discharge end of the magazine until the lock is restored to locking position.

9. In a typographical composing machine equipped with a matrix feeler movable across the discharge end of the magazine in the absence of protruding matrices, the combination of matrix feeler actuating means, an assembling mechanism mounted on a hinged frame for movement from and to its operative position, a lock to hold the frame in its operative position, an auxiliary lock to prevent the release of the frame lock, and means controlled by the matrix feeler actuating means in the movement of the feeler across the discharge end of the magazine to disable the auxiliary lock and permit the release of the frame lock.

10. A combination according to claim 9 including means controlled by the release of the frame lock to lock the matrix feeler in actuated position across the discharge end of the magazine.
